UNITED STATES PATENT OFFICE.

ROBERT L. DORAN, OF NASHVILLE, TENNESSEE.

HYDROCARBON LIGHTING APPARATUS.

SPECIFICATION forming part of Letters Patent No. 628,079, dated July 4, 1899.

Application filed March 22, 1898. Serial No. 674,746. (No model.)

To all whom it may concern:

Be it known that I, ROBERT L. DORAN, a citizen of the United States, residing at Nashville, in the county of Davidson and State of Tennessee, have invented certain new and useful Improvements in Hydrocarbon Lighting Apparatus; and I do hereby declare the following to be a full, clear, and exact description of the invention, such as will enable others skilled in the art to which it appertains to make and use the same.

My invention relates to lighting apparatus employing hydrocarbons for fuel; and the improvement consists in certain means and devices for preheating and feeding the fuel to the burners, as will be fully described hereinafter.

The objects of my invention are, first, to produce a hydrocarbon-lamp that shall be capable of producing a brilliant white light with small consumption of fuel; second, to provide means for heating, vaporizing, and mixing the oil with air before it is admitted to the burner, and, third, to provide an auxiliary heating device or generator that shall normally keep the oil in the main generator at a suitable temperature for lighting when the lights are not in use. I accomplish these objects by means of the devices shown in the drawings, in which similar figures of reference designate similar parts in the several views.

Figure 1 is an elevation of the improved lamp. Fig. 2 is a similar view, enlarged, with the casing of the mixing-tube removed. Fig. 3 is an enlarged side view of the same, partly in section, the section being taken on the line A B of Fig. 2. Fig. 4 is an elevation of a one-burner light, showing a generator adapted thereto. Fig. 5 is a side view of the same.

40 The main supply or generator pipe 1, through which the oil-supply is fed under pressure to the lamp, passes near the burner 2, which may be of any usual incandescent type, and terminates in an atomizing-valve 3, which can be regulated to deliver a fine spray of vapor into the opening of the air-mixing chamber 4.

An auxiliary pipe 1^a, which takes its supply of oil from the pipe 1 or other suitable source, passes along pipe 1 and, returning under its 50 self, terminates in a series of holes or burners 5, located beneath pipe 1 and beneath its own intermediate portion.

The vaporized oil discharged from the atomizing-valve 3 is received by the mixing tube or chamber 4 and is thence delivered to the 55 burner 2, which is preferably provided with a gauze cover or screen, above which the oil-vapor is burned. In practice I prefer to cover the flame above the burner with an incandescent mantle of suitable form for intensifying 60 the light.

The operation of my invention is as follows: Oil is admitted to pipe 1^a by a valve or other means and is ignited upon reaching the burners 5. The flame thus produced heats the 65 part of pipe 1^a above the burners, and the oil thus heated upon reaching the burners produces a still hotter flame. This flame is preferably small and is designed to act as a continuous heater or generator for the main supply-pipe 1. When it is desired to light the lamp, the valve of the main supply-pipe is opened, and the oil thus admitted to the main generator flows through the pipe above the continuous-generator flame and is heated. 70 The oil then flows to the atomizing-valve 3, from which it is ejected in the form of heated vapor or spray. This vapor entering the mixing-chamber 4 becomes mixed with a portion of atmospheric air, and the mixture of oil and 75 air discharges through the gauze cover of the burner 2 under the mantle, where it is ignited by the flame of the continuous generator.

The intensity of the flame and the brilliancy of the light may be closely regulated by the 85 atomizing-valve, which may be of any approved style, but is preferably a needle-valve of fine pitch.

In lamps of the kind described it is essential that suitable means be provided for easily 90 and quickly lighting the lamp. I accomplish this purpose by means of the continuous generator above described, which keeps the oil in the main generator at a temperature sufficiently high to insure its atomizing readily by 95 passing through the atomizing-valve when the main supply is turned on, and thus producing a heated mixture of oil-vapor and air that is readily ignited by contact with the flame of the continuous generator, thus lighting 100 the lamps automatically.

By bending the continuous-generator pipe 1^a underneath itself and locating the burners in its lower part, as shown in Figs. 2, 3, 4,

and 5, the flame of these burners not only heats the oil supplied to the atomizing-valve by the main pipe 1, but also heats its own supply in the bend of pipe 1^a above the burner, 5 generating the necessary heat from a very small quantity of oil.

The continuous heater or generator above described, by which the main oil-supply for the lamp may be continually kept at the desired 10 temperature and by which the main burner may be automatically lighted, forms an essential feature of my invention, and this I desire to secure by Letters Patent. I do not desire to confine my invention to the particular 15 form of continuous generator shown, as I consider the details of its construction immaterial, it being only essential to the spirit of my invention that the main oil-supply of the lamp be continuously heated by an auxiliary 20 heater or generator placed beneath the main supply-pipe of the lamp and adapted to heat not only the main pipe, but the auxiliary supply-pipe also when the lamp itself is not lighted.

25 What I claim as my invention, and desire to secure by Letters Patent, is—

1. In a hydrocarbon lighting apparatus, the combination of a mixing-chamber having an

open end, a burner communicating with said mixing-chamber, a main vapor-generator pipe 30 having connected therewith an atomizing-valve arranged to discharge into the open end of the mixing-chamber, and an auxiliary vapor-generator pipe having a portion bent on itself and provided with burners for heating both the main generator-pipe and auxiliary generator-pipe, substantially as described.

2. In a hydrocarbon lighting apparatus, the combination of a mixing-chamber having an open end, burners communicating with said 40 mixing-chamber, mantles for said burners, a main vapor-generator pipe extended between the mantles and provided with an atomizing-valve arranged to discharge into the open end of the mixing-chamber, and an auxiliary vapor-generator pipe having a portion bent on itself adjacent to the main generator-pipe and provided with burners for heating both generator-pipes, substantially as described.

In testimony whereof I affix my signature 45 in presence of two witnesses.

ROBERT L. DORAN.
